UNITED STATES PATENT OFFICE.

WILLIAM W. DEAN, OF ELYRIA, OHIO; CURTIS B. CAMP, TRUSTEE, APPOINTED BY COURT.

ELECTROMAGNET STRUCTURE.

1,125,489.

Specification of Letters Patent.

Patented Jan. 19, 1915.

Application filed September 8, 1904. Serial No. 223,638.

To all whom it may concern:

Be it known that I, WILLIAM W. DEAN, a citizen of the United States, residing at Elyria, in the county of Lorain and State of Ohio, have invented certain new and useful Improvements in Electromagnet Structures, of which the following is a specification, reference being had therein to the accompanying drawing.

10 My invention relates to electromagnet structures, and particularly to the means for supporting, adjusting and controlling the armatures thereon. It is applicable to all electromagnets, whether single or double 15 pole, single or double spool, but I shall illustrate and describe it as applied to a telephone ringer and to a relay of present standard commercial type. These two are fairly representative, the first of double 20 spool electromagnets and the second of single spool magnets.

It is the object of my invention to provide simple and easily manipulated means 25 (1) for supporting and adjusting an armature with regard to the pole or poles of the magnet by which it is moved, and (2) for preventing the armature from sticking or freezing to the pole of the magnet. Referring 30 particularly to the polarized ringers used in connection with telephone instruments, the armature support and adjustment is a matter of some importance, for upon it depends the certainty as well as the force 35 of the strokes upon the gongs. The armature is usually carried in a yoke, and the methods of supporting this yoke have been many and various. The basic idea underlying all of them has been to form a frame 40 carrying the magnet cores with their spools, and also carrying the armature and the permanent magnet by which the parts are polarized. In many cases it has been proposed to support the armature upon the frame by adjustable connections independent of the 45 magnet cores; but this is open to the obvious criticism that since the armature then bears no direct relation to the cores the adjustment is not secure, for any slight derangement or displacement of either the frame or the cores is likely to displace the armature 50 with relation to said cores. In order to maintain the adjustment under all conditions, I directly connect the armature support and the cores, uniting the latter in fact 55 performing the function of a frame, and thus

not only doing away with several superfluous elements, but strengthening the entire structure, as the iron cores when yoked together at both ends form a very strong and rigid frame. Mounting the support directly 60 upon the cores, I then secure my adjustment by making them relatively movable. The most convenient as well as the most reliable method of adjustment is by a screw feed, but I have found that to produce the necessary 65 screw threads in the iron core itself is somewhat expensive and not entirely satisfactory. I therefore provide a sleeve, which for convenience is formed upon one of the spool-heads, and herein lies the gist 70 of my invention, for this sleeve serves both to support the yoke by means of nuts threaded upon itself, and as a distance piece to prevent the armature from striking the end of the core. This latter function is 75 commonly performed by a rivet of non-magnetic metal fitted in the end of the armature, or by a strip of similar metal interposed between the armature and core. My device is better because it requires no 80 punching or drilling of the parts, and because the metal spool-heads are forced upon the cores mechanically and hence can be set with undeviating accuracy to leave the end of the core in every case a predetermined 85 distance below the end of the sleeve, thus securing uniformity in the air gaps.

To put it in a word, I attain my object by providing an armature yoke adjustably mounted upon the magnet spool-head, which 90 projects a little beyond the end of the core.

My invention is illustrated in the accompanying drawings, wherein—

Figure 1 is a side view of a complete 95 ringer embodying my invention. Fig. 2 is a detail view of the armature and its supporting structure, with parts shown in section. Fig. 3 is a side view of a standard telephone relay with my improved distance piece.

In the drawings, C, C are the iron cores 100 of a pair of ringer magnets, supported and rigidly connected at their lower ends by the iron yoke bar A'. This bar A' serves 105 as the base for the entire ringer structure, all the parts being supported thereon and therefore bearing a definite relation to it and to each other; however they may be adjusted. Upon the opposite ends of this bar I mount the gong posts g, g, which carry 110 the gongs G, G. Upon each core I provide

a suitable winding W , which is connected in circuit in the usual manner to be traversed by alternating or other suitable operating current, whereby to produce the proper magnetic effects in the cores C . These windings are confined upon the cores between the spool-heads S and w , the latter being of suitable insulating material as usual. Lying beneath each of the upper heads S I provide an insulating auxiliary head w' , which prevents any possibility of short-circuiting or grounding by the magnet windings on the metal heads S .

Between the gongs G plays the clapper a^2 , carried upon the clapper rod a' , which is rigidly connected at the opposite end to the iron armature A , overlying the magnet poles, and supported by pivot screws a^3 carried in the upturned ears a^4 of the yoke a . This yoke is of non-magnetic metal, of sufficient length to span the ends of the cores C , and at each end is provided with a circular opening a^5 forming a ring which encircles the end of one of the cores. Each spool-head S has an upwardly extending sleeve S' , which may be formed integral with the head, as shown in the left hand side of Fig. 2, or may be formed separately and riveted or otherwise secured to the head as shown at s^2 in the right hand side of Fig. 2. Each sleeve S' is externally threaded, and fitted thereto are the nuts or screw-rings s, s' , of hexagonal or other convenient shape to be set up by a wrench. The ends of the yoke a encircles the sleeves S' , and each lies between one pair of the adjusting nuts or rings s, s' .

The armature A when made according to my invention is unprovided with copper rivets or other distance devices, being left plain in this respect. Its ends are prevented from striking the magnet poles, however, by the upper edges of the sleeves S' , which project a short distance beyond the ends of the cores C , forming a circumscribed definite air gap d . The yoke a , spool-heads S , sleeves S' , adjusting rings s' , are all formed of non-magnetic metal such as brass; hence there is no possibility of the armature either striking the ends of the cores C or sticking to any of the parts carried thereby.

The armature A and the cores C, C are polarized by means of a permanent magnet M , both of whose ends are returned or bent over, the lower one, m , being suitably attached to the yoke bar A' , and the upper one overlying the armature A . It will be observed that while I have thus reduced the number of parts of my frame, I have preserved its rigidity, and have provided for maximum efficiency. The upper arm of the permanent magnet M may be brought down to lie as close to the armature as the limits of adjustment will permit.

After assembling the ringer I have thus

described, the proper armature adjustment is secured by manipulating the threaded rings or nuts s, s' , and these are then set up tightly, binding the yoke a between them and rendering the adjustment permanent and reliable.

In Fig. 3 I have shown my non-magnetic spool-head applied to the core 2 of a standard telephone relay. In this case the armature 1 is shown supported upon the frame 75 of the relay, so as to be directly included in the magnetic circuit. It may obviously be carried upon a yoke or frame supported upon the spool-head 3, however, in the same manner as shown with respect to the ringer 90 in Fig. 1. The circular flange or sleeve 4 surrounding the core extends a short distance beyond the end of the latter, as in the ringer, forming a fixed and predetermined air gap. In this or any other case the air gap may be made adjustable, if desired, by making the sleeve or flange movable upon the head, by making the latter movable upon the core, being forced upon and supported by the cores of the magnets, but it is evident 95 that this is not essential, as many ways might be resorted to without departing from the scope of my invention. The essential features of my invention consist in the adjustable support of the armature yoke upon the upper spool-heads, and in the projection of the spool-head sleeves to form distance pieces. These features I have claimed broadly, and I wish it distinctly understood that I am fully aware of the possibility of 100 changing non-essential features of construction, and of applying the essential features to other forms of magnet than those I have herein shown and described. All such changes and applications are contemplated 105 by me as within the scope and purview of my invention and of my claims.

Having thus described my invention what I claim and desire to secure by Letters Patent is:

1. An electromagnetic structure comprising a core, a winding, a spool head, supporting means integral with the spool head and encircling the core, clamping means carried thereby and an armature supporting member adjustably supported in operative relation to the core by such supporting and clamping means.

2. An electromagnetic structure comprising a magnet spool, heads therefor, a core, supporting means carried by one of said heads and encircling the core of said magnet, and an armature supporting means adjustably supported in operative relation to the core by such supporting means.

3. In an electromagnet structure, a core, a spool head upon the core, supporting means mounted on the spool head and encircling the core, an armature support adjusting means therefor mounted upon said

supporting means, and an armature supported in operative relation to the core by such armature support.

4. An electromagnet structure comprising a core, a spool-head having a sleeve encircling said core, a supporting yoke adjustably mounted on said sleeve, and an armature carried upon said yoke in operative relation to said core.

10 5. An electromagnet structure comprising a core, a spool-head having a sleeve surrounding said core and provided with screw-threads, an armature support having a portion encircling said sleeve, nuts clamping the same thereon, and an armature carried upon said support.

20 6. An electromagnet structure comprising a core, an armature in operative relation thereto and a spool-head encircling the core below its end and provided with a projecting portion adapted to limit the approach of the armature to the core.

25 7. An electromagnet structure comprising a core and a winding therefor, an armature in operative relation to the core, a spool-head thereon, a non-magnetic sleeve surrounding the end of the core and extending into position to limit the approach of the armature thereto.

30 8. An electromagnet structure comprising a core and a winding therefor, an armature in operative relation to the core, and a spool-head having a non-magnetic sleeve extending beyond the end of the core.

35 9. An electromagnet structure comprising a core, a spool-head thereon formed of non-magnetic material and provided with a sleeve extending beyond the core, an armature support adjustably mounted upon said sleeve, and an armature carried upon said support.

40 10. A ringer comprising a pair of cores and a yoke bar connecting them at one end, spool-heads for the cores mounted at the opposite ends thereof, a yoke extending across and adjustably secured upon the heads and an armature carried upon the yoke.

45 11. An electromagnet comprising a pair of cores, a pair of sleeved non-magnetic spool-heads thereon, a yoke having perforated ends surrounding the sleeves of said spool-heads, adjusting and locking means

therefor, and an armature mounted upon said yoke.

50 12. An electric bell comprising a yoke bar, gongs carried upon said bar, a pair of electromagnets also carried upon said bar, a pair of spool-heads for said magnets having screw-threaded sleeves, a yoke having its ends perforated and encircling the sleeves, 60 nuts upon said sleeves to adjust and lock the yoke thereon, and an armature pivotally supported upon said yoke.

65 13. An electric bell comprising a frame, gongs supported upon said frame, a pair of electromagnets also supported upon the frame, spool-heads for said magnets of non-magnetic material and provided with projecting sleeves surrounding and extending beyond the cores of the magnets, a yoke supported upon said sleeves, and an armature pivoted upon said yoke in operative relation to the magnets, together with a clapper actuated by the armature, substantially as described.

70 14. An electromagnet structure comprising a core and an armature, a non-magnetic supporting device surrounding the core having a projection adapted to prevent contact between the armature and core, together with means to connect the armature adjustably through said support with the core, substantially as described.

75 15. In a magneto-bell ringer, the combination of electromagnets having cores presenting projecting end portions, supporting sleeves carried by said end portions, an armature support comprising a yoke having openings to receive said sleeves, and adjustable nuts on each of said sleeves clamping the yoke between them.

80 16. In an electromagnet structure, a core, a spool head on said core, a supporting means integral with said spool-head, an adjustable member on said supporting member, an armature and an armature support carried by said adjustable member.

In testimony whereof I affix my signature in presence of two witnesses.

WILLIAM W. DEAN.
